UNITED STATES PATENT OFFICE.

HENRY M. WILLIS, OF HEMPSTEAD, NEW YORK.

COMBINED POCKET-KNIFE AND MANICURING-TOOL.

No. 870,604.

Specification of Letters Patent.

Patented Nov. 12, 1907.

Application filed November 30, 1906. Serial No. 345,825.

To all whom it may concern:

Be it known that I, HENRY M. WILLIS, a citizen of the United States, residing in Hempstead, in the county of Nassau and State of New York, have invented 5 certain new and useful improvements in a Combined Pocket-Knife and Manicuring-Tool, of which the following is a specification.

The invention consists in providing the blade spring of a pocket knife with means for filing or rasping the 10 edge of the finger or toe nail, and to provide in connection with the filing or rasping means, a guide and a gage for controlling the position of the nail during the filing or rasping operation relatively to the surface of the rasping means. Provision of means for paring said 15 nail is also comprehended within the purview of this invention as is also the provision of means for removing from under the nail objectionable substances.

The accompanying sheet of drawings, forming a part of this specification therefore shows such "pocket-knife" displayed in various positions to clearly illustrate the applicability of the invention.

Figure 1 illustrates an elevational view of a pocket-knife, the improvement thereto applied, Fig. 2 shows such a knife in position during one of the manicuring 25 operations; Fig. 3 illustrates another position of the knife, displaying how the device may be employed to reach the more inaccessibly located portions of the nail—down in the corners and near the quick; Fig. 4 illustrates such a knife with the back portion thereof presented to view and illustrating the filing or rasping surface created on one side of the knife's blade-spring, and further illustrating different characters of filing surfaces either coarse or fine or straight or oblique for both 30 cutting and filing the nail. Fig. 5 illustrates a transverse sectional view through lines 5—5 of Fig. 1, and which shows the depression of the blade-spring and the rising edges of the casing which are adapted for use as guide and gage respectively; Fig. 6 illustrates the same kind of a knife provided with means both for paring 35 the nail and for removing therefrom under objectionable substances.

In the several illustrations, similar characters of reference will apply to the similar parts.

Describing the invention in the form illustrated, the 45 blade-spring 8, of a "pocket-knife", so-called, is provided with a rasping or filing surface 9, which may, in the present instance, be divided into portions 10 and 11, for both cutting the nail, and for smoothing the same after it has been cut.

50 As will be understood, the spring 8, controls the movements, in the present instance, of blades 12, and one of the important features of the invention is comprised in sinking or depressing the spring 8, sufficiently within or beneath the back-edges 13 and 14 of the 55 knife-case-sides 15 and 16, so that the edges will project beyond or from the surface of the spring's filing

surface 9 to permit the use of said edges 13 and 14 being employed as a guide and gage respectively to control the position of the nail relatively to the filing surface, whereby to keep the nail on the file, and also 60 prevent the cutting of the nail too short, by depositing the ball-end of the finger on either edge 13 or 14 during the process of either drawing the knife across the finger or the finger across the knife as best suits the individual.

65 The rasping or filing surface, carried by the spring 8, as has been intimated, may be divided into portions 10 and 11 respectively, so that the corrugations upon one portion, for instance that designated 23, may be cut transversely at right or substantially at right angles 70 to the longitudinal axis of the spring 8, while those on portion 24 may be cut obliquely across the spring, the latter operating to cut the nail, at will, while the former operates to smooth the same after cutting. This feature, of course, while assisting in the completeness of 75 things, does not necessarily operate in the interpretation of the invention whether employed or not.

75 Referring now, more particularly to Fig. 6, we have additions of means for paring the nail, and means for removing from under the nail the usual objectional substances. The end 17, of the one wall of the knife-case may be provided with an opening 18, a portion of the wall 20 of which may be constructed to form a cutting surface at the intersection of that wall and the wall of the casing-side, whereby the nail may be 80 trimmed while the trimming passes through the opening 18. The means for removing objectionable substances from under the nail may comprehend a prong 21, which may be formed integrally with the body of the casing-side at the extremity of the same, preferably in such a manner that the free end of that prong may be disposed within the line of that end, whereby to lessen the likelihood of that prong rendering damage to the pocket while the knife is being carried. In order to provide for this, a portion 22 may be removed from 85 the knife's end and into the recess formed by this removal, and the prong located as more clearly seen in the figure referred to. It is understood, however, that the particular arrangement here set forth does not necessitate adoption.

90 100 It will now be seen that I have converted a knife—a so-called "pocket-knife"—into a nail-file or manicuring instrument, so as to form a combined pocket-knife and manicuring tool.

Having thus described this invention, I claim, and 105 will regard as an infringement of my rights any device which the following protection can cover:

1. In a so-called pocket-knife, the combination with a handle and blades, of a blade-spring, located between the sides of the handle, and which is provided with a finger-nail-filing surface, said surface being depressed below the sides of the knife-handle.
2. In a so-called pocket-knife, the combination with a 110

handle and blades, of a blade spring located between the sides of the knife-handle, and which is provided with a finger-nail-filing surface, said surface being located beneath the edges of the sides of the knife-handle, so that said edges will form guides and gages respectively for the ball of the finger.

3. A so-called pocket-knife, having the upper or outer side of the blade-spring provided with suitable rasping facilities for trimming the nails of fingers and toes, and 5 having said spring so embedded between the side portions of the knife case that the portions of said case that project outward from the filing or rasping surface will form guides and gages respectively for controlling the position of the nail relatively to the filing surface, 10 whereby to keep the nail onto the file and also prevent 15

too great an abrasion of said nail, and means for paring the nail.

4. A so-called pocket-knife, comprising blades, a casing for the blades and a spring, said spring being set beneath the edges of said casing and provided with a rasping 20 surface, and said edges forming a guide and gage respectively to control the body to be rasped relatively to the rasping surface.

Signed at New York, the county and State of New York this 20th day of November, 1906.

HENRY M. WILLIS.
